Primary Examiner — Steven J Czyz*(74) Attorney, Agent, or Firm* — Gregory Finch; Finch Paolino, LLC(57) **CLAIM**

The ornamental design for a magnetic connector attachment, as shown and described.

DESCRIPTION

FIG. 1 is an isometric view of the claimed magnetic connector attachment, embodying the present design;

FIG. 2 is a front side view thereof;

FIG. 3 is a rear side view thereof;

FIG. 4 is a right side view thereof;

FIG. 5 is a left side view thereof;

FIG. 6 is a top down plan view thereof; and,

FIG. 7 is a bottom up plan view thereof; and,

FIG. 8 is an alternative isometric view thereof.

The broken lines depict portions of the article that form no part of the claimed design.
